COMBINED MULTI-STAGE CENTRIFUGAL COMPRESSOR AND MULTI-COOLER HOUSING FOR COMPRESSING AIR AND OTHER GASES

Zoltan P. Nyeste, Grand Island, Peter G. Wendt, Williamsville, and John K. Kilbane, East Aurora, N.Y., assignors to Worthington-CEI, Incorporated, Buffalo, N.Y.

Filed Apr. 24, 1972, Ser. No. 247,229

Term of patent 14 years

Int. Cl. D15—02

U.S. Cl. 65—1 A

FIG. 1

FIG. 2

FIG. 4

FIG. 3

FIG. 5

FIG. 6

FIG. 7

FIG. 8

FIG. 1 is an isometric view taken from the front and right side of a combined multi-stage centrifugal compressor and multi-cooler housing showing our new design,

FIG. 2 is an isometric view taken from the rear and left side thereof,

FIG. 3 is a right side elevational view thereof,

FIG. 4 is a front elevational view thereof,

FIG. 5 is a left side elevational view thereof,

FIG. 6 is a rear elevational view thereof,

FIG. 7 is a top plan view thereof, and

FIG. 8 is a bottom plan view thereof.

We claim:

The ornamental design for a combined multi-stage centrifugal compressor and multi-cooler housing for compressing air and other gases, substantially as shown.
